HAND SCYTHE FOR CUTTING GRASS OR THE LIKE

James A. Sinclair, The Jimsin Co., P.O. Box 238,
Franklin, La.

Filed May 13, 1960, Ser. No. 60,576

Term of patent 14 years

(Cl. D40—1)

FIGURE 1 is a perspective view of a hand scythe for cutting grass or the like embodying my new design.

FIGURE 2 is a view in side elevation thereof;

FIGURE 3 is a top plan view thereof;

FIGURE 4 is a transverse sectional view taken on line 4—4 of FIGURE 2; and

FIGURE 5 is a transverse sectional view thereof taken on line 5—5 of FIGURE 2.

The design for my hand scythe disclosed herein is characterized by the smooth continuous taper of both the handle portion and the blade portion, the progressively varying oval cross-sectional shape of the handle portion, and the shape of the handle end portion remote from the blade, all as shown.

I claim:

The ornamental design for a hand scythe for cutting grass or the like, substantially as shown and described.
